TRANSOM OPERATOR

Elmer Edward Koenig, Garfield Heights, and
Warner Gustav Hult, Cleveland, Ohio

Application February 8, 1932, Serial No. 591,676

4 Claims. (Cl. 268—116)

This invention relates to a transom operator adapted to open panels and windows that are not easily accessible, and is more particularly designed to operate a transom or ventilator window provided in a partition wall, either in conjunction with a door or separately.

Transom operators heretofore constructed are generally very complicated in their mechanism and costly to manufacture and install. Many turns of the operating handle, particularly in the worm and gear type of operator, have been necessary to effect a ninety degree opening of the window. This turning operation to effect opening of the window is not only annoying, but time consuming, and further, necessitates the use of complicated mechanism which often gets out of order. Furthermore, transom operators heretofore constructed are often lacking in effective means to prevent unauthorized opening of the window by manual manipulation of the window itself. As a consequence, unauthorized entry to rooms by manipulating the transom window from the outside is sometimes effected.

An object of our invention is to provide a transom operator by means of which a ninety degree opening of the transom can be effected by a short turn of the operating handle.

Another object of our invention is to provide a transom operator which is adapted to be installed and concealed entirely within the ordinary hollow metallic post without necessitating changes in the post itself.

Another object of our invention is to provide a transom operator having means operable to effect automatic locking of the transom window in closed position and to prevent opening thereof by manipulation of the window itself, and having means adjustable to firmly resist movement of the window in any position except through proper manipulation of the operating handle.

Still another object of our invention is to provide a transom operator composed of few parts, which is positive in operation, inexpensive to manufacture and install, sturdy and lasting in construction and substantially foolproof.

Other objects of this invention will become evident as the description proceeds.

Although the novel features which are believed to be characteristic of this invention will be particularly pointed out in the claims appended hereto, the invention itself, as to its objects and advantages, and the manner in which it may be carried out, may be better understood by referring to the following description taken in con-

nnection with the accompanying drawing forming a part thereof, in which

Fig. 1 is a vertical face view of a fragmentary portion of the partition wall showing our novel transom operator in dotted lines, operably connected to the transom window and shown as it appears within the partition post;

Fig. 2 is a horizontal cross-sectional view through a hollow metallic partition post and our transom operator, this view being taken on line 10 2—2 of Fig. 3 in the vicinity of the operating handle;

Fig. 3 is an enlarged vertical interior view of a fragmentary portion of a hollow metallic post showing particularly the means for mounting the 15 lower end of our transom operator within the partition post;

Fig. 4 is an enlarged vertical cross-sectional view through a portion of the hollow post and transom operator, this view being taken on line 20 4—4 of Fig. 3;

Fig. 5 is an end view of a fragmentary portion of the transom window and transom operator, showing particularly the manner in which our transom operator is connected to the transom 25 window, this view further illustrating the positions which the transom window assumes when the transom operator is in certain positions.

Like reference characters denote like parts in the several figures of the drawing.

Referring more particularly to the drawing, we have shown our transom operator as mounted within a hollow metallic partition post and operably connected to a transom window in a partition panel, but it is understood that this is merely illustrative and a door may take the place of the panel 23. It is understood, however, that our transom operator may be operably connected to any pivoted panel, window or other wall section desired to be manipulated into various positions, 40 within the purview of this invention. For the purpose of illustration, therefore, we have shown a portion of a partition post comprising hollow metallic uprights 10 and 11 maintained in spaced relationship by the spacer member 12. As clearly 45 shown in Fig. 2, spacer member 12 is provided with shoulder portions 13 at each of the four corners thereof which engage respectively the in-turned flanges 14 of uprights 10 and 11 respectively. A clip element 15 is positioned on each 50 side of the post and is provided with shoulder portions 16 which seat against the inner corners 17 of the uprights 10 and 11 respectively. A screw bolt 18 extends through the clips 15 on each side of the post and when nut 19 on the end thereof 55

is properly manipulated, the clip elements 15 can be drawn tightly against the corners 17 of the post uprights 10 and 11 and in conjunction with spacer 12 firmly clamp the uprights 10 and 11 in 5 fixed spaced relationship. The spacer member 12 may be provided with upturned flanges 20 along each side thereof through which the screw bolt 18 may extend.

Pilaster covers 21 extending the full length of 10 the post can be snapped into engagement with the shoulder portions 16 of the clips 15 to cover the space between the spaced uprights 10 and 11, making a finished and attractive appearing metallic post.

15 A transom bar 22 extends between the uprights 10 and 11 of two spaced posts and is suitably secured thereto. A wall panel 23 is secured along the edges thereof to the transom bar 22 and within a recess 24 provided in the post uprights. 20 The upper end of the post uprights 10 and 11 are secured to a cornice member 25 which extends horizontally across the top of the partition.

The transom panel or window comprises horizontal framing members 26 and vertical framing members 27 forming together a frame within which the window panel 28 is seated. The transom window 28 is pivotally mounted upon stud elements 29 having spaced flanges 30 which are secured to the vertical framing members 27 of 30 the panel. The window panel is thus adapted to pivot about a horizontal axis. It is understood that the stud elements 29 can be attached to the window panel 28 in any position to produce the desired vertical or horizontal tilting of the window panel. The stud elements 29 project into the vertical posts and are suitably mounted in bearings provided in the post uprights.

The specific construction of our transom operator will now be described. A shaft 31 is provided 40 which extends through an aperture 32 in one of the pilaster covers 21 and into the hollow post. An operating handle 33 is suitably secured to the outer end of the shaft 31. The operating handle may be provided with a reduced portion 34 if desired, which portion may extend through the aperture 32 and engage the end of the shaft 31 within. The shaft 31 may be mounted for rotating movement in any suitable manner within the hollow post. We have shown in the drawing means 50 which have proven as a satisfactory mounting for the shaft 31, which consists of a U-shaped support having upstanding side walls 35 connected by a web portion 36. The U-shaped support is concealed within the post and rests upon the spacer member 12, as clearly shown in Fig. 4. When thus arranged, the screw bolt 18 may also extend through the side walls 35 of this U-shaped support, thus firmly securing the same immovable within the post. The shaft 31 extends through 60 aligned apertures in the flange portions 35, which apertures constitute bearings for the shaft.

The shaft 31 is provided with a squared portion 36 which extends through a corresponding squared aperture in a crank element 37. The 65 crank element 37 rotates with the rotation of the operating handle 33. The lower end 38 of a connecting rod 39 is pivotally secured to one end of the crank element 37 by means of a pin 40.

The connecting rod 39 extends up through the 70 hollow post member and the upper end 41 thereof is pivotally connected to a crank arm 42 by means of pivot pin 43. The crank arm 42 is provided with a bushing portion 44 into which the free end of one of the stud elements 29 extends and is 75 secured.

It is now seen that by turning the handle operator 33, crank element 37 vertically manipulates the connecting rod 39 so as to turn the crank arm 42 which is fixedly secured to the stud 29 attached to the window panel, and thus the 5 window panel may be swung about a horizontal axis. It is further evident from a study of Figs. 3 and 5, that a ninety degree turn of the handle operator 33 will turn the crank element 37 approximately ninety degrees. The connecting rod 10 39 in turn rotates the crank arm 42 approximately ninety degrees which will move the window panel 28 approximately ninety degrees, or from closed position to full open position, as indicated in Fig. 5.

15 The crank element 37 is preferably so arranged that when the window panel 28 is closed, the crank element stands in a true vertical position. By turning the handle operator 33 so as to move the crank element 37 beyond dead center vertical position, shown in Fig. 3, the window panel 28 is effectively locked in closed position and all attempts to manually manipulate the window panel to open the same will be thwarted. This is true by reason of the fact that any attempt to 25 pivot the window panel into open position will have a tendency to produce a downward thrust on the connecting rod 39, which will only move the crank element 37 further beyond vertical dead center. To limit the dead center movement 30 of the crank element 37, we provide a pin 45 which extends through the flange portions 35 of the U-shaped support and against which extension 46, provided on the crank element 37, abuts. Therefore, once the crank element 37 has been moved 35 beyond dead center position by the handle operator 33, the window panel is locked in closed position against movement in the opposite direction, and because of the shoulders 51 and 52, which are a part of the transom sill and abut 40 against opposite sides of the longitudinal faces of the transom panel, it can not be swung further, and therefore cannot be externally manipulated.

To maintain the window panel in any desired 45 open position, we provide a brake device comprising a metallic band 47 which encircles a portion of the shaft 31. The band 47 is provided with a pair of laterally extending arms 48 which straddle a pin 49 extending between and secured to the flange portion 35 of the U-shaped support. 50 A screw bolt 50 extends through the laterally extending arms 48. By proper manipulation of a nut 51 at the end of the screw bolt 50, it is seen that the band 47 may be adjusted with respect to the shaft 31 which it encircles so as to 55 grip the shaft any amount desired. It is relatively easy to overcome the gripping action produced on the shaft 31 by the band portion 47 through the handle, but any movement of the window panel 28 through direct application of 60 force to the window panel itself is firmly resisted if not made impossible by the braking action of the band 47. By increasing the length of the operating handle 33, so as to obtain the proper leverage the braking force exerted by the brake 65 band 47 can be made inconsequential when the window panel is properly operated through the operating handle.

Our novel transom operator is composed of 70 relatively few parts which can be inexpensively manufactured and assembled. It is sturdy and substantially foolproof in construction, can be installed by unskilled workmen, and can be concealed in a small amount of space within the post member. We have eliminated all gears, racks and 75

other mechanical elements which are likely to get out of order. The panel window can be moved any desired amount by a slight and quickly executed movement of the handle and it may be automatically locked in closed position by a slight further movement of the operating handle.

While certain novel features of the invention have been disclosed and are pointed out in the annexed claims, it will be understood that various omissions, substitutions and changes may be made by those skilled in the art without departing from the spirit of the invention.

What is claimed is:

1. In combination with partition framing including hollow post members and a panel pivotally mounted on stud elements projecting into said hollow post members, of panel operating mechanism including a crank arm connected to one of said stud elements, an operating handle mounted on the outside of one of said posts, a shaft connected to said handle and extending into said post, a crank member connected to said shaft within said post, a link connecting said crank arm and crank element, a brake including a reversely bent strap frictionally embracing said shaft to resist movement of said panel, and means including a member passing between the end portions of the strap and fixed relative to said stud elements for holding said strap against movement.
2. In combination with partition framing including hollow post members and a panel pivotally mounted on stud elements projecting into said hollow post members, of panel operating mechanism including a crank arm connected to one of said stud elements, an operating handle mounted on the outside of one of said posts, a shaft connected to said handle and extending into said post, a crank member connected to said shaft within said post, a link connecting said crank arm and crank element, and a brake including a spring strap frictionally embracing said shaft to resist movement of said panel and having end portions extending in the same general

direction, and means for varying the distance between said end portions for adjusting the grip of said strap on said shaft.

3. In combination with partition framing, including hollow post members and a panel pivotally mounted on stud elements projecting into said hollow post members, of panel operating mechanism including a crank arm connected to one of said stud elements, an operating handle mounted on the outside of one of said posts, a crank element connected to said handle, a rod operatively connected to said crank arm and crank element, said panel operating mechanism being adjusted so that a ninety degree turn of the handle will pivot the panel through substantially ninety degrees and a turn of more than ninety degrees of the handle will lock the panel in fixed position and a brake including means frictionally engaging the shaft to which the operating handle is connected to resist movement of said panel.

4. In combination with partition framing, including hollow post members and a panel pivotally mounted on stud elements projecting into said hollow post members, of panel operating mechanism including a crank arm connection to one of said stud elements, an operating handle mounted on the outside of one of said posts, a crank element connected to said handle, a rod operatively connected to said crank arm and crank element, said panel operating mechanism being adjusted so that a ninety degree turn of the handle will pivot the panel through substantially ninety degrees and a turn of more than ninety degrees of the handle will lock the panel in fixed position, a brake including a bent strip frictionally embracing the shaft to which the operating handle is connected, to resist movement of said panel and means including a member passing between the end portions of the strap and fixed relative to said stud elements for holding said strap against movement.
